(57) CLAIM

The ornamental design for a golf towel assembly, as shown and described.

DESCRIPTION

FIG. 1 is a top and front perspective view of a golf towel assembly showing our new design;

FIG. 2 is a front view thereof;

FIG. 3 is a rear view thereof;

FIG. 4 is a left-side view thereof;

FIG. 5 is right-side view thereof;

FIG. 6 is a top view thereof;

FIG. 7 is bottom view thereof;

FIG. 8 is a top and front perspective view of an alternate configuration of the golf towel assembly thereof, with the detachable towel removed from the multipaneled main towel;

FIG. 9 illustrates the golf towel assembly of FIG. 1 in an environment of use, attached to a golfclub bag; and,

FIG. 10 illustrates the golf towel assembly of FIG. 1 in an environment of use, with the detachable towel removed from the multipaneled main towel.

The broken lines in the drawings depict portions of the golf towel assembly that form no part of the claimed design. The broken lines showing a golf club bag in FIGS. 9 and 10 depict environment and form no part of the claimed design.

1 Claim, 8 Drawing Sheets
